FOLDING BED

Walter Hand, Memphis, Tenn.

Application April 5, 1945, Serial No. 586,739

2 Claims. (Cl. 5—99)

1

This invention relates to folding beds, and more particularly to a folding bed for small children in which it is necessary or desirable that the bed be of crib type, with side walls in addition to the usual end walls, in order that a small child may not fall out of the bed.

In such beds it is known to fold the bed during periods when its use is not desired, by turning the mattress on one side edge, folding the ends around the ends of the mattress and bringing the front side against the mattress. The desired level of the mattress as a bed however, is ordinarily such that when this is done the back edge of the mattress must be lowered as folding progresses or the front edge will undesirably project above the sides.

The objects of the present invention are:

To make a bed of simple yet rugged construction which may be compactly folded when not in use and which when so folded will house the mattress entirely below the top of the sides and this without the necessity of establishing a low level for the mattress when the bed is in use.

A further object of the invention is to provide simple and efficient supporting means for the mattress, and means which will automatically engage the support to prevent accidental tipping of the mattress when in use.

A further object is to provide a simple and efficient support for the back edge of the mattress when the mattress is vertically disposed, which will permit shift of the mattress without interference.

The means by which the foregoing and other objects are accomplished, and the manner of their accomplishment, will readily be understood from the following specification upon reference to the accompanying drawings, in which:

Fig. 1 is a transverse sectional elevation of the bed with the mattress and supporting frame in position for use, shown in elevation.

Fig. 1A is a similar transverse sectional elevation of a portion of the bed showing the latching arrangement hereinafter described.

Fig. 1B is a fragmentary sectional elevation on the line 1B—1B of Fig. 1.

Fig. 2 is a similar transverse section with the front side of the bed lowered, and the mattress turned into vertical position precedent to folding in the ends and reducing the width of the structure.

Fig. 2A is a fragmentary sectional plan on the line 2A—2A of Fig. 2.

Fig. 3 is a front elevation somewhat less than one-half of the bed in folded position; and

2

Fig. 4 a longitudinal sectional elevation, with the mattress removed, of about the same amount of the opposite end portion of the bed with the mattress support in bed position.

Fig. 5 is a fragmentary plan view of the folded bed.

Referring now to the drawings in which the various parts are indicated by numerals:

The bed includes a back, ends and a front. 10 The back has end posts 11 which are interconnected by upper and lower rails 13 and 15 forming a rectangular frame which is completed by vertically disposed slats or bars 17. The ends comprise sections rigidly attached to the back, 15 and relatively much wider folding sections hinged to the rigid sections. Each rigid section has a top rail 19, a bottom rail 21, and a front post 23, the rails being mortised into or otherwise secured to one or the other of the back posts 20 11, at the front post 23, which latter post terminates at its lower end substantially flush with the bottom of the rail 21. The frame formed by the posts and rails is preferably filled by a panel 25, though bars similar to the bars 17, may be used. The sections are preferably braced from the back to give additional rigidity as by corner braces 27.

The wider folding sections each comprise a back post 29, a front post 31, a top rail 19A, and 30 a bottom rail 21A, forming a frame which may be filled by a panel 33, though if preferred, bars similar to the back bars 17 may be used. Preferably as illustrated in Figs. 1B and 2A the back post 29 is flared outward at its lower end 29A in order that when the sections are folded the posts will give a slightly wider base against overturning.

Hinging of the post 29 to the rigid section may be effected at the top through an upwardly extending pin 29B and a plate 35 overlying and secured to the rail 19, and apertured to receive the pin. Immediately below the rails 21, 21A the post 29 may be rounded to form a second pivot pin 29C which is embraced by the two halves 37A, 45 37B of a member, apertured to embrace the pin, and the lower end 29A of the post be continued therebeyond. Around the end of the member is a strap 39 held in place as by a bolt 39A, the member being secured to the underside of the 50 rail 21.

The front side of the bed comprises a frame of length to be disposed between the front posts 31, the frame having top and bottom rails 41, 43, side rails 45 and bars 47, and being provided at 55 its opposite ends with pairs of straps 49 which

extend into overlying relation with the posts 31 and are notched for detachable engagement with headed pins 51 projecting from the posts. An additional set of pins 51A may be provided if it is desired to establish the front at a different level. Similar pins 53 project from the posts 29 which pins are used to support the front when the ends of the bed are in folded position.

Secured to the posts 11 and 23 at the opposite ends of the bed and at desired bed level are plate-like members 55, which carry inwardly projecting pivot pins 57. Secured to the lower rails 21A of the folding post of the bed are other plate-like members 59 which extend upward along the posts 31 and are secured to and steadied thereby, these latter members being provided with notches 61 in their upper ends to engage pins similar to the pins 51. Pivotally secured to the members 59 adjacent the notches are latches 63 which have side notches 65 adapted to engage and lock pins 75 seated in the member notches, against dislodgment. The upper ends of the latches are beveled so that the pins 75 displace them as the pins approach the notches 61, and the lower ends of the latches are heavier than the upper ends so that the latches are biased by gravity to return to upright position and latching engagement with the pins 75 when the pins seat notches 61. In Fig. 1A the plate-like member 59 is shown broken away to reveal the details of latch 63.

A mattress 67 is carried by a support frame having side and end members 69 and 71, preferably angle irons, integrally joined at the frame corners and a mattress underlying structure, as of springs 73. The end members 71 are pivotally supported by the pins 57, the back ends of these members cantilevering rearward of the pins. Adjacent their forward ends the members carry pins 75 which engage the notches 61 when the mattress and support frame are swung to bed level and in turn are engaged and locked in such position by the notches 65 of the latches. At the rear of the support frame a stop for the rear edge of the mattress preferably includes top and bottom rails 77, end rails 79 and dowels 81 secured into the top and bottom rails. The bottom rail of the stop seats on the rear side of the bed frame and is connected thereto by hinges 83. The upper ends of the end rails 79 are arcuately beveled and the upper edge of the top rail may be also so beveled. Arcuately curved guides 85 are disposed against the inner sides of the lower end rails 21 and the posts 11 to form tracks for the arcuate upper ends of the end rails 79. The braces 27 are butted against these guides and the lower rail 15 of the back frame, and secured thereto.

For use, the straps 49 of the front are detached from the pins 53, the front is removed and the folding portions of the bed ends are opened out. The mattress 67 and support are then swung forward and downward about the pins 57 as centers, the upper rail 77 of the stop being guided against interference with the back of the bed by the guides 85. The pins 75 projecting from the end rails 71 engage the beveled upper ends of the latches 63 as they near seating position, displace these latches and come to rest in supporting position in the notches 61, the latches being re-

turned by gravity to effect locking engagement of the latch notches 65 with the pins and preventing accidental folding of the mattress under load on the cantilevered back edge thereof. The notches of the straps 49 on the front are then engaged with the pins 51 and the front secured in place, or, should it be desired to have the front lower, the strap notches may be engaged with the lower set of pins 51A and the front secured in such lowered position. It will be noted that with the front secured, sufficient displacement of the latches 63 cannot be had to effect their disengagement from the pins.

To fold the bed it is necessary first to remove the front, then manually release the latches 63 and hold them released until the pins 75 of the mattress support are raised above the latches, after which further folding is carried out.

I claim:

1. A folding bed including a back wall, foldable end walls, a detachable front, a mattress and a mattress support frame; said end walls each including a section rigidly attached to said back, and a section hinged to the forward edge of said rigid section and inwardly foldable into parallelism with said back, means respectively pivotally attaching the opposite ends of said mattress support frame intermediate its width to said fixed end sections adjacent the forward edges of said sections, means respectively at opposite ends of said frame adjacent its outer edge, and complementary means carried by said folding sections engageable by said frame means, in open position of said folding sections, for supporting said frame in bed position, and means biased for latching engagement with said frame means in supported position.

2. A folding bed including a back wall, foldable end walls, a detachable front, a mattress and a mattress support frame; said end walls each including a section rigidly attached to said back, and a section hinged to the forward edge of said rigid section and inwardly foldable into parallelism with said back, means respectively pivotally attaching the opposite ends of said mattress support frame intermediate its width to said fixed end sections adjacent the forward edges of said sections, means respectively at opposite ends of said frame adjacent its outer edge, and complementary means carried by said folding sections engageable by said frame means, in open position of said folding sections, for supporting said frame in bed position.

WALTER HAND.
